UNITED STATES PATENT OFFICE.

JOHN PRUE KARNS, OF BOULDER, COLORADO.

HEADING-MACHINE.

1,271,321.

Specification of Letters Patent. Patented July 2, 1918.

Application filed October 4, 1915. Serial No. 54,042.

To all whom it may concern:

Be it known that I, JOHN P. KARNS, a citizen of the United States, residing at Boulder, in the county of Boulder and State of Colorado, have invented a new and useful Heading-Machine, of which the following is a specification.

The device forming the subject matter of this application is adapted to be employed, primarily, but not exclusively, for boring 10 blast holes into the breast of a mine working.

One object of the present invention is to provide means for imparting a combined 15 reciprocating and rotary movement to the cutter shaft.

Another object of the invention is to provide novel means for moving longitudinally of the machine, for adjustment, a carriage 20 comprising a cylinder and a piston, the latter being operatively connected with the cutter shaft.

Another object of the invention is to improve the nut and abutment construction 25 wherewith co-operates the feed screw whereby the movement of the carriage is controlled.

It is within the province of the disclosure to improve generally and to enhance the 30 utility of devices of that type to which the present invention appertains.

With the above and other objects in view which will appear as the description proceeds, the invention resides in the combination 35 and arrangement of parts and in the details of construction hereinafter described and claimed, it being understood that changes in the precise embodiment of the invention herein disclosed can be made without 40 in the scope of what is claimed, without departing from the spirit of the invention.

In the accompanying drawings:

Figure 1 shows in side elevation, a heading machine embodying the present invention;

Fig. 2 is an end elevation of the machine, looking toward the rear end thereof;

Fig. 3 is a vertical longitudinal sectional view showing a portion of the truck, the 50 view depicting particularly the means whereby the truck is held against movement, and the means whereby the carriage on the truck is advanced manually, at the will of an operator;

Fig. 4 is a fragmental top plan of the machine;

Fig. 5 is a cross section taken on the line 5—5 of Fig. 4;

Fig. 6 is a fragmental horizontal section taken through the nut in which the feed screw works;

Fig. 7 is a top plan of the multi-part nut with which the feed screw co-operates;

Fig. 8 is a sectional view showing the rear portion of the sleeve in which the cutter 65 shaft works;

Fig. 9 is a cross section on the line 9—9 of Fig. 8;

Fig. 10 is a cross section on the line 10—10 of Fig. 8;

Fig. 11 is a cross section on the line 11—11 of Fig. 8;

Fig. 12 is a sectional detail showing the forward end of the sleeve or casing in which the cutter shaft operates;

Fig. 13 is a cross section on the line 13—13 of Fig. 12;

Fig. 14 is a cross section on the line 4—4 of Fig. 12;

Fig. 15 is a cross section on the line 15—15 of Fig. 4, parts being omitted.

In Fig. 1 of the drawings, the numeral 1 indicates the breast of a mine working in which is formed a bore 2. The floor of the mine is indicated at 3 and carries track rails 4 adapted to be traversed by the wheels 5 of a truck 6 embodying transverse U-shaped brackets 7 carrying upper guides 8 and 9 and lower guides 10 and 11. The bottoms of the brackets 7 support a lower track 12. As shown in Fig. 1, certain of the brackets 7 may be secured to the lower track 12 by means of braces 14. The brackets 7 carry opposed side tracks 15. One end of the truck is provided with a head plate 16 adapted to abut against the breast 1 of the working, the head plate ordinarily being supported by the track 12 and the guides 8—9—10—11.

In order to prevent the truck from shifting its position on the track rails 4, and to maintain the head plate 16 in abutment with the breast 1 there is provided a releasable holding mechanism embodying a pair of hangers 17 attached to the guides 8 and 9, the hangers supporting pivotally mounted clevises 18, to which are pivoted rods 19 threaded into sleeves 20. Rods 21 are threaded into the sleeves 20 and are pivoted to open sided clips 22 adapted to engage the track rails 4 and to grip the same, in a manner which will be clearly understood from

Fig. 3, the rods 19 and 21 and the sleeves 20 forming turnbuckles which, being tightened up, prevent a retrograde movement of the truck and serve to hold the head plate 5 16 in abutment with the breast 1.

Mounted to move for adjustment on the truck, longitudinally of the truck, but ordinarily held fixed with respect thereto, is a carriage denoted generally by the numeral 10 23, the carriage being a composite structure. The carriage 23 comprises a cylinder 24, ordinarily constituting a part of a compressed air motor of the reciprocating piston type. Secured to the forward end of the 15 cylinder 24 is a rear sleeve 25, to the forward end of which is secured an intermediate sleeve 26, the intermediate sleeve carrying a forward sleeve 27.

Especial attention being given to Figs. 12, 20 13 and 14 of the drawings, it will be observed that the forward sleeve 27 comprises separable, trough-shaped parts 28 and 29. Seated in a groove in the forward end of the sleeve 27 is a washer 30. Mounted in a 25 groove 32 in the part 29 of the sleeve 27 is a half-ring 31 disposed opposite to a half-rib 33 on the part 28. To the rear of the elements 33 and 31, the forward sleeve 27 is provided with a circumscribing internal 30 recess 34 in which is mounted for rotation, at times, but against longitudinal movement, a collar 35, spaced antifrictionally from the sleeve 27 by means of balls 36. Circumscribing the collar 35 and constituting a part thereof is a ratchet wheel 37 35 adapted to be engaged by a pawl 38 pivoted to the part 28 of the forward sleeve 27. Disposed within the contour of the collar 35 is a tubular ball cage 39 receiving balls 40, engaged in seats 40^a formed in the 40 interior of the collar 35.

Noting Figs. 8, 9, 10 and 11, it will be seen that the rear sleeve 25 embodies coöperating trough-shaped parts 41 and 42. In the rear 45 sleeve 25 near to the forward end thereof is fashioned an internal circumscribing recess 43 in which is mounted for rotation, at times, but held against longitudinal movement, a collar 44 spaced from the sleeve 25 antifrictionally by means of balls 45. The collar 44 carries an external ratchet wheel 46 adapted to be engaged by a pawl 47 pivoted to the part 41 of the sleeve 25. At this point it may be stated that the construction 50 last above described resembles the pawl and ratchet mechanism shown in Fig. 14, saving for the fact that the teeth of the ratchet wheels 46 and 37 face in opposite directions, the pawls 47 and 38 being mounted accordingly. Disposed within the collar 44 is a 55 tubular ball cage 48 carrying balls 49 seated in recesses 49^a in the interior of the collar 44. The pawls 38 and 47, together with the collars 44 and 35 and attendant parts 60 constitute pawl and ratchet mechanisms, the

functions of which will be made manifest hereinafter.

Behind the recess 43 is a half-ring 50 which is seated in a groove 51 formed in the part 42 of the sleeve 25, the half-ring 70 coöperating with a half rib 52 on the part 41 of the sleeve. The sleeve 25 is provided with grooves 53 in which are seated buffers 54 which may be made of hard rubber or some substance having the necessary resiliency. The buffers 54 are retained by two-part washers 55 shown clearly in Fig. 10.

The part 29 of the forward sleeve 27 carries wheels 56 adapted to coöperate with the bore 2 and adapted to coöperate with the 80 tracks 15 if the carriage 23 is retracted sufficiently on the truck. The cylinder 24 may be equipped with wheels 57 which coöperate with the side tracks 15 on the truck. The carriage 23 comprises, further, a single 85 wheel 58 adapted to traverse the lower track 12 on the truck.

Mounted to reciprocate in the cylinder 24 is a piston 59, the rod 60 of which, as shown in Fig. 8 is provided with a socket 90 61 receiving one end of a rod 62 held in place by a key 63. The rod 62 passes loosely through an opening 64 formed in one end of a main cap 65 held by means of a key 66 to one part 67 of a cutter shaft. 95 In its interior and upon its rear wall, the main cap 65 is rounded as shown at 68 to coöperate with a rounded washer 69 on the rod 62, the washer being held in place by an abutment 70 retained by a nut 71 housed 100 in a chamber 72 formed in an auxiliary cap 73 located within the main cap 65, the forward end of the auxiliary cap 73 and the rear end of the part 67 of the cutter shaft being rounded as shown at 74. From the 105 foregoing it will be observed that the rod 62 is connected with the part 67 of the shaft by what amounts to a ball and socket joint, such a structure giving the necessary movements, should the part 67 of the cutter shaft 110 and the rod 62 be disposed slightly out of axial alinement.

The cutter shaft embodies a forward part 75 carrying, at its exposed extremity, a cutter head 76 of any desired construction. In 115 the rear end of the shaft 75 is fashioned a socket 77 in which the forward end of the part 67 of the cutter shaft is received, the constituent members of the shaft being held together for simultaneous rotation by means of a key 78. The part 75 of the shaft, as shown in Fig. 8 is equipped with spaced shoulders 110, adapted to coöperate respectively with the buffers 54, should the cutter shaft make a sufficiently long stroke, a 120 contingency arising, for instance, when the cutter head 76 fails to strike the forward end of the bore 2.

The shaft 75-67 is mounted for longitudinal reciprocation and for rotation in the 130

washer 30, the rib 33 and the half-ring 31 of Fig. 12, in the ball cage 39 of said figure, in the ball cage 48 of Fig. 8, in the rib 52 and the corresponding part 50 and in the 5 buffers 54.

In the part 75 of the cutter shaft are fashioned straight longitudinal grooves 79 receiving the balls 49 which are interengaged with the collar 44. In the part 75 10 of the cutter shaft are disposed spiral grooves 80 coacting with the balls 40 which are interengaged with the collar 35.

Noting particularly Figs. 6 and 5, it will be seen that an abutment 81 is carried by 15 the guides 8-9-10-11 for adjustment longitudinally of the machine, the abutment 81 being provided with a recess 82. The abutment 81 is held in adjusted position by means of keys 83, engaged in openings 84 20 in guides 9 and 11, keys 85 cooperating with the abutment 81 and the guides 8 and 10 to aid in holding the abutment in place, the parts 8 and 9 being provided as shown at 86 in Fig. 4, with openings which receive 25 the keys 85. Across the rear end of the recess 82 in the abutment 81 extends a back plate 87, held to the abutment by means of a U-bolt 88 having an intermediate head 89. Disposed within the recess 82 of the abutment 30 81 is a four-part nut 90, the constituent members of which are provided along their forward and rear faces with flanges 91 engaging the upper and lower edges of the back plate 87 and the intermediate forward portion of the abutment 81. The constituent members of the nut 90 are held in place by means of bolts 92. Interposed between the sides of the multi-part nut 90 and the side walls of the recess 82 in the abutment 35 81 are wedges 93 and 94. The nut 90 may be shifted transversely and be held in adjusted position by means of the wedges 93 and 94.

Passing through the head 89 of the U-bolt 40 88 and through the forward portion of the abutment 81 and threaded into the multi-part nut 90 is a feed screw 95 to the forward end of which is secured a disk 96 having openings 97 adapted to receive pins 98 45 formed in the interior of a worm wheel 99 held for rotation in a circumscribing groove 100 formed in a head 101 on the rear of the cylinder 24 and in a cap 102 secured to the head. In the head 101 is fashioned a curved recess 103, the edge of the disk 96 being shaped to conform to the curvature of this recess. Journaled for rotation in the head 101 and in the cap 102 is a transverse shaft 104 carrying a worm 105 meshing into the 50 worm wheel 99. The ends 106 of the shaft 104 are adapted to receive a crank 107.

In practical operation, when the piston 55 59 is drawn rearwardly, the cutter shaft 75-67 is drawn rearwardly also. When the cutter shaft 67-75 is drawn rearwardly, the col-

lar 35 is held against rotation, due to the coaction between the ratchet wheel 37 and the pawl 38. The balls 40, traversing the spiral grooves 80, impart a slight rotation to the cutter shaft 67-75 as the latter is retracted. During this retracting movement of the shaft 67-75, the collar 44 rotates with the shaft, being interlocked therewith through the instrumentality of the balls 49 and the straight grooves 79, the pawl 47 75 clicking over the ratchet wheel 46 due to the fact that the ratchet wheels 46 and 37 operate in opposite directions. When, however, the cutter shaft 67-75 is advanced, then the pawl 47 will hold the collar 44 80 against rotation, and the latter, through the medium of the balls 49 will hold the shaft 67-75 against rotation, the shaft advancing by a straight line movement, as distinguished from a combined advancing and rotary movement. When the shaft 67-75 is advanced, the collar 35 rotates upon the shaft, the pawl 38 clicking over the ratchet wheel 37.

From the foregoing it will be understood 90 that the cutter shaft 67-75 and the piston 59 reciprocate, and that the shaft rotates as it is retracted, the cutter head 76 fashioning the bore 2 as the shaft is advanced. During this operation, the carriage 23 is not advanced and retracted, because the same is held against longitudinal movement by the co-operation between the feed screw 95 and the multi-part nut 90. Neither does the truck move bodily on the track rails 4, because the truck is held by the turnbuckle construction 19-20-21. At times it may be desirable to advance the carriage 23 on the truck, and when such an operation is desired, the feed screw 95 is rotated by means 105 of the worm wheel 99, the worm 105, the shaft 104 and the crank 107, the feed screw traversing the multi-part nut 90 and advancing the carriage 23, the wheels 57 of which move along the tracks 15, the wheel 110 58 moving along the track 12 and the wheels 56 traversing the bore 2.

The position of the abutment 81 longitudinally of the carriage may be adjusted by mounting the keys 83 and 85 successively in 115 the openings 84 and 86.

Although the shaft 75 and the cap 65 rotate, the rod 62 and the piston 60 do not rotate, especial attention being directed to the element 70 of Fig. 8, and attendant parts, 120 whereby such an operation is possible.

Having thus described the invention, what is claimed is:—

1. In a mining machine, a truck; a track carried by the truck; a carriage mounted 125 to move along the track; a cutter assembled with the carriage; an abutment mounted on the truck for adjustment longitudinally of the truck; means connecting the abutment with the truck for holding the abutment in 130

adjusted positions longitudinally of the truck; a nut mounted in the abutment; a feed screw threaded into the nut; means under the control of an operator for actuating the feed screw; and means for connecting the feed screw with the carriage for rotation but against movement longitudinally of the carriage.

2. In a mining machine, a truck; a track carried by the truck; a carriage mounted to move along the track; an abutment mounted on the truck for adjustment longitudinally of the truck; means connecting the abutment with the truck for holding the abutment in adjusted positions longitudinally of the truck; a nut carried by the abutment; a feed screw threaded into the nut; means for connecting the feed screw with the carriage for rotation but against movement longitudinally of the carriage; a worm wheel assembled with the feed screw and journaled in the carriage; and a worm disposed transversely of the feed screw and assembled with the rear end of the carriage and meshing into the worm wheel.

3. In a mining machine, a truck; a track carried by the truck; a carriage mounted to move along the track; a cutter assembled with the carriage; an abutment mounted on the truck; a nut assembled with the abutment; a feed screw threaded into the nut and provided with a ball head, the rear end of the carriage comprising a member hav-

ing a recess in which the head rocks; a worm wheel in said member; means for pivotally assembling the worm wheel with the head; and a worm journaled in said member and meshing into the worm wheel.

4. In a mining machine, a truck including transverse brackets; a track carried by the lower portions of the brackets; a carriage; means on the carriage for engaging the track slidably; other tracks carried by the side portions of the brackets; means on the carriage for engaging the last specified tracks slidably; guides carried by the side portions of the brackets; an abutment slidably received by the brackets; means connecting the abutment and the guides for holding the abutment in adjusted positions on the guides longitudinally of the guides; a nut carried by the abutment; a feed screw threaded in the nut; means under the control of an operator for actuating the feed screw; a cutter mounted on the carriage; and means for connecting one end of the feed screw with the carriage for rotation but against movement longitudinally of the carriage.

In testimony that I claim the foregoing as my own, I have hereto affixed my signature in the presence of two witnesses.

JOHN PRUE KARNs.
